UNITED STATES PATENT OFFICE.

THOMAS J. MITCHELL AND JAMES A. McCREARY, OF UNIONTOWN, PENNSYLVANIA.

LATCH FOR TELESCOPIC SECTIONS.

1,125,866.

Specification of Letters Patent.

Patented Jan. 19, 1915.

Application filed August 30, 1913. Serial No. 787,540.

To all whom it may concern:

Be it known that we, THOMAS J. MITCHELL and JAMES A. McCREARY, citizens of the United States, residing at Uniontown, in the county of Fayette and State of Pennsylvania, have invented certain new and useful Improvements in Latches for Telescopic Sections, of which the following is a specification.

10 The present invention relates to an improved latch mechanism which is adapted to be employed in connection with telescoping sections or members such as are frequently embodied in discharging rams for coking ovens, such a discharging ram being shown by Patent No. 891,850 which was granted to us June 30, 1908 for improvements in coke oven apparatus, the object of this invention being to provide a latch mechanism 15 which embodies novel features of construction whereby each telescoping section is securely locked in a retracted position until after the preceding section has been completely projected and the two sections 20 locked together for unitary movement.

A further object of the invention is to provide a device of this character which is comparatively simple and inexpensive in its construction, which is positive and reliable 25 in its operation, and which requires no adjustment or particular attention on the part of the operator.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following 40 description and accompanying drawings, in which:—

Figure 1 is a longitudinal sectional view through the telescoping sections of a coke 45 oven discharging ram constructed in accordance with the invention, the inner telescoping section being shown as fully projected and in position for being locked with the next telescoping section, and portions 50 being broken away and shown in section to more clearly illustrate the invention. Fig. 2 is a similar view showing the position assumed by the parts when the telescoping sections are being retracted and slightly before the outer section has been completely 55 retracted so that the inner section must be

unlocked therefrom. Fig. 3 is a detail view of the latch roller upon the outer telescoping section, and Fig. 4 is an enlarged transverse sectional view on the line 4—4 of 60 Fig. 1.

Corresponding and like parts are referred to in the following description and indicated in all the views of the drawings by the same reference characters.

Specifically describing the present embodiment of the invention, the reference character A indicates the fixed casing or housing which is rigidly mounted in some suitable manner upon the support, the said 70 housing being shown as formed of the vertical side plates 1 and the top plate 2, angle irons 3 being provided for connecting the upper edges of the side plates 1 to the top plate 2, and reinforcing angle irons 4 being applied to the lower edges of the side plates 1. An outer telescoping member B is slidably mounted for longitudinal movement within the casing A, in any suitable manner such as that shown by our prior Patent No. 891,850 which was granted to us June 30, 1908 for improvements in coke oven apparatus. This outer telescoping member B is shown as composed of the two spaced I beams 5 and the top plate 6.

An inner telescoping member C is slidably mounted for longitudinal movement within the outer telescoping member B, the said telescoping member C being shown as composed of the spaced channel irons 7 and 80 a top plate 8. At suitable intervals in the length of the inner telescoping member C, trunnions or journals 9 project from opposite sides therefrom, the said journals carrying the rollers or wheels 10 which engage 85 the inner faces of the I beams 5 and serve to support the inner telescoping member C upon the telescoping member B.

A bearing plate 11 is secured to the inner 100 face of one of the I beams 5, the said bearing plate being provided with a stub shaft or trunnion 12 upon which a roller 13 is journaled. This roller 13 is adapted to be engaged by a hooked detent 14 for the purpose of locking the outer telescoping member B in a retracted position until after the 105 inner telescoping member C has been fully projected. The hooked detent 14 is carried by a transverse shaft 15 which is journaled in suitable bearings 16 which project downwardly from the reinforcing angle irons 4 at the bottom of the housing A, and rigid

with the hooked detent 14 is a arm 17 which is provided at the extremity thereof with a roller 18. The arm 17 and hooked detent 14 project in opposite directions from the 5 shaft 15, and when the arm 17 is forced downwardly, as indicated by Fig. 1, the hooked detent 14 is moved upwardly into operative position so as to engage the roller 13 and securely retain the telescoping member 10 B in a retracted position.

The lower faces of the I beams 5 are provided with racks 19, and a rack plate 20 is applied to the bottom of the inner telescoping member C, the central portion of the 15 plate 20 being provided with the teeth 20^a, while the side portions of the rack plate upon each side of the teeth 20^a are smooth as indicated at 20^b. When the hooked detent or latch member 14 is in operative position, 20 as indicated by Figs. 1 and 3, the roller 18 of the lever 17 travels upon one of the smooth side portions 20^b of the rack plate 20.

The inner telescoping member C is provided toward the inner end thereof with a 25 vertically disposed locking bolt 21 which is slidably mounted upon a suitable guide member 22, the upper end of the locking bolt projecting through an opening in the top of the inner telescoping member C and 30 terminating in an anti-friction roller 23 which is adapted to travel upon the lower face of the top plate 6 of the outer telescoping member B. The lower end of the locking bolt 21 is pivotally connected at 24 to 35 one end of a lever 25 which extends longitudinally of the inner telescoping member C and is pivotally mounted at an intermediate point in its length upon the transverse pivot rod 26. The opposite end of the lever 40 25 is provided with a suitable counter-weight 27 and has a cam face 28 upon the lower side thereof.

When the inner telescoping member C has 45 been fully projected so that the rack 20^a thereof is about to escape from the main driving pinion 29 which may be mounted in any suitable manner, the locking bolt 21 is brought into registry with an opening 30 formed in the top plate 6 of the outer telescoping member B. A reinforcing plate 31 is applied to the top of the said plate 6 at the rear edge of the opening 30, while a stop 32 is applied to the lower face of the plate 6 at the opposite side of the said opening. 50 The nose of the locking bolt 21 engages the stop 32 when the bolt is in registry with the opening 30, and the action of the counter-weight 27 then causes the locking bolt to be moved upwardly so that the nose thereof 55 enters the opening 30. The roller 18 at the end of the arm 17 at the same time escapes from the inner end of the telescoping member C so as to permit of the hooked detent or latch member 14 dropping into an inoperative 60 position and releasing the roller 13

of the telescoping member B. The two telescoping members B and C are thus securely locked together so as to have a unitary movement and the outer telescoping member B released from the housing A so as to be moved outwardly with the inner telescoping member C. As soon as the outer telescoping member B has been slightly advanced the racks 19 thereof are brought into engagement with the main driving pinion 75 29 so that the members may be advanced by a continuous rotary movement of the said driving pinion.

The usual ram may be attached to the telescoping member C, and when it is desired to retract the telescoping members, the driving pinion 29 is rotated in a reverse direction. As soon as the outer telescoping member B has been completely retracted, the driving pinion 29 is brought into engagement with the cam face 28 of the lever 25 so as to move the counter-weighted end of the lever upwardly and retract the locking bolt 21 from engagement with the opening 30 of the plate 6. In this connection it 80 may be noted that the lever 25 projects downwardly through a longitudinal slot 33 formed in the rack plate 20 so that the cam face 28 of the lever will be engaged by the driving pinion 29 as just described upon the 85 retraction of the telescoping members, while when the inner telescoping member C has been fully projected, the end of the lever 25 may be engaged by the driving pinion 29 to assist the counter-weight 27 in throwing 90 the locking bolt 21 upwardly into operative position. When the telescoping members are being retracted, the engagement of the driving pinion 29 with the cam face 28 95 serves to lift the counter-weight 27 and withdraw the locking bolt 21 from operative position so as to release the inner telescoping member C from the outer telescoping member B. A cam or inclined face 34 at the inner extremity of the telescoping member 100 C is also brought into engagement with the roller 18 of the arm 17 so as to force the said lever downwardly and swing the hooked detent 14 upwardly into operative position. The telescoping member B is then securely locked in a retracted position and the inner telescoping member C released therefrom so as to be completely retracted 110 within the outer telescoping member B. It will thus be obvious that by rotating the 115 driving pinion 29 in one direction the several telescoping members may be projected in regular order and coupled together for unitary movement, while upon reversing the direction of rotation of the driving pinion 29 the telescoping members may be retracted and uncoupled in the reverse order.

Having thus described the invention, what we claim as new and desire to secure by Letters Patent, is:—

1. A discharging mechanism for coke ovens and similar structures, including a fixed member, separate telescoping sections arranged one within the other, a driving element common to said sections for successively projecting the same, an automatically operating locking device partly controlled by the driving element and having means for coupling and uncoupling the separate sections, and an independently operated latching device including a relatively stationary element on one telescoping section, a movable element carried by said fixed member, and an element carried by one of said telescoping sections and coöperating with said movable element to engage it with said stationary element.

2. A discharging mechanism, for coke ovens and similar structures, including a fixed casing member, separate telescoping sections arranged one within the other, a driving element common to said sections for successively projecting the same, an automatically operating locking device partly controlled by the driving element and having means for coupling and uncoupling the separate sections, and an independently operated latching device including a relatively stationary element on one telescoping section, a swinging hooked detent carried by the fixed member and adapted to normally disengage itself from said stationary element, and a cam element carried by one of said telescoping sections and coöperating with said detent element to engage it with said stationary element.

3. The combination of a housing, telescoping sections mounted within the housing, means for successively projecting the telescoping sections in regular order, a swinging latch member upon the housing for engagement with the outer telescoping section to retain the same in a retracted position, an arm rigid with the swinging latch member, and cam means upon the inner telescoping section for coöperation with the arm to move the latch into operative position and retain it in such position when the telescoping members are retracted, the latch member being released to unlock the outer telescoping section when the inner telescoping section has been completely projected.

4. The combination of a housing, telescoping sections mounted within the housing, means for successively projecting the telescoping sections in regular order, a swinging latch member carried by the housing for engagement with the outer telescoping section, an arm rigid with the latch member

and provided with a roller, a track upon the inner telescoping section which engages the roller to hold the latch member in operative position when the telescoping sections are retracted, the roller escaping from the end of the track and releasing the latch member when the inner telescoping section has been completely projected.

5. The combination of a housing, telescoping sections mounted within the housing, means for successively projecting the telescoping sections in regular order, a swinging latch member for engagement with the outer telescoping section to retain the same in a retracted position, an arm controlling the latch member, a roller upon the arm, a track upon the inner telescoping section for engagement with the roller to retain the latch in operative position when the telescoping sections are retracted, the roller escaping from the end of the track and releasing the latch member when the inner telescoping section has been completely projected, and cam means upon the inner telescoping section for bringing the roller back into engagement with the track when the telescoping sections are again retracted.

6. The combination of a housing, telescoping sections mounted within the housing, means for successively projecting the telescoping sections in regular order, a hooked latch member pivotally mounted upon the housing, a roller upon the outer telescoping section for engagement with the hooked latch member to retain the outer telescoping section in a retracted position, an arm rigid with the latch member, a roller upon the arm, a track upon the inner telescoping section for engagement with the roller to retain the latch member in operative position, the roller escaping from the end of the track to release the latch member when the inner telescoping section has been completely projected, and cam means upon the inner telescoping section for bringing said roller back into engagement with the track when the telescoping sections are again retracted.

In testimony whereof we hereunto affix our signatures in the presence of two witnesses.
